CLAIM

The ornamental design for a headlight for vehicle, as shown and described.

DESCRIPTION

1. Headlight for vehicle

Figure 1: Perspective

Figure 2: Front

Figure 3: Back

Figure 4: Left

Figure 5: Right

Figure 6: Top

Figure 7: Bottom

The claimed design is installed to the left and right sides of the front of an automobile; the cover parts of the front of this article are transparent.

The broken lines shown in the drawings depict portions of the headlight for vehicle that form no part of the claimed design.
